UNITED STATES PATENT OFFICE.

OTTO A. HOKANSON, OF WOODSTOCK, ILLINOIS, ASSIGNOR TO WOODSTOCK TYPEWRITER COMPANY, OF WOODSTOCK, ILLINOIS, A CORPORATION OF ILLINOIS.

BACK SPACER FOR TYPEWRITERS.

Application filed August 25, 1921. Serial No. 495,330.

To all whom it may concern:

Be it known that I, Otto A. Hokanson, a citizen of the United States, residing at Woodstock, in the county of McHenry and 5 State of Illinois, have invented certain new and useful Improvements in Back Spacers for Typewriters, of which the following is a specification.

This invention relates to mechanism for 10 moving the platen carriage of a typewriter in a reverse direction, a letter space at a time, and is especially applicable to typewriters in which the platen carriage is movable into a compacted position.

15 The invention has for its object the provision of mechanism of the class named which shall be of improved construction and operation. It is exemplified in the combination and arrangement of parts shown in the 20 accompanying drawings and described in the following specification, and is more particularly pointed out in the appended claims.

In the drawings—

25 Fig. 1 is a vertical sectional view of a portion of a typewriter showing one embodiment of the present invention applied thereto;

30 Fig. 2 is a fragmentary view of a portion of the typewriter illustrated in Fig. 1 and shows the back spacer mechanism in top plan; and

35 Fig. 3 is a vertical section of a portion of a typewriter showing the back spacer mechanism in elevation.

40 In the figure of the drawings, the numeral 10 designates the main or base frame of a typewriter having arms 11 pivoted at 12 thereon and carrying a platen carriage frame 13. Ways 14 are formed on the frame 13 and a platen carriage 15 is arranged to travel along the ways 14. An escapement wheel 16 is journaled on the frame 13 and is provided with a pinion 17 which meshes with a rack 18 for controlling the movement 45 of the platen carriage. Any suitable escapement mechanism may be provided for the escapement wheel 16. A back spacing key 19 is pivoted at 20 on the frame 10 and is provided with an upwardly extending arm 21 arranged to engage one arm 22 of a bell crank lever 23 pivoted at 24 on a bracket 25 supported on the frame 10. The other arm 26 of the bell crank 23 is pivotally connected at 27 to one end of a link 28. The 50 opposite end of the link 28 is pivoted at 29 to a crank arm 30 having a slot 31 arranged to engage a screw 32 for both sliding and rotary movement. The screw 32 is supported on a bracket 33 in a position concentric with the axis of the sprocket wheel 16 when 60 the platen carriage frame is in its operating position.

A spring 34 normally draws the link 28 to the right and rearwardly, as viewed in Fig. 2. The movement of the link to the 65 right is limited by the end of the slot 31, and the rearward movement is limited by a pin 35 secured to the link in position to strike the edge of the crank arm 30. When 70 the back spacing key is depressed the link 28 will be moved to the left causing the slot 31 to slide on the screw 32. The pivotal connection 29 between the link 28 and the crank arm 30 is extended upwardly to a level 75 with the teeth on the ratchet wheel 16. The movement of the link 28 to the left will bring the pin 29 into engagement with one of the teeth on the ratchet wheel. As soon 80 as the righthand end of the slot 31 contacts with the screw 32 further movement of the link 28 to the left will cause the crank arm 30 and the pin 29 to rotate about the axis 85 of the screw 32 in a clockwise direction, as viewed in Fig. 2, carrying with it the escapement wheel 16. Since the screw and escapement wheel are concentric with one another the pin 29 will travel about the same center as the tooth with which it is engaged. The movement of the pin 29 is limited 90 by a lug 36 bent downwardly from the end of the crank arm 39 which engages a stop 37 projecting from the bracket 33. The movement is sufficient to rotate the escapement wheel an amount corresponding to one 95 letter space and the escapement wheel will, of course, be retained in the position in which it is rotated by the escapement dogs. Since the escapement wheel is moved in a reverse direction to its letter feeding movement the platen carriage will be spaced backwardly, one letter space for each operation of the back spacing key. A spring 38 is provided for the back spacing key to return 100 it to its uppermost position after each operation thereof.

105 It will be seen that the back spacing mechanism is mounted entirely on the main frame of the machine and does not in any way interfere with the folding movement of the platen carriage frame. The move- 110

ment of the frame into its operating position automatically brings the escapement wheel into position to co-act with the back spacing pin 29.

5 I claim:—

1. A typewriter comprising a pair of relatively movable frame parts, a platen carriage having escapement mechanism mounted on one of said parts, and back spacing mechanism for said platen carriage mounted on the other of said parts, said back spacing mechanism being positioned to cooperate with said escapement mechanism when said platen carriage is in operating position. 10
2. A typewriter comprising a main frame, a platen carriage frame pivotally mounted on said main frame and having escapement mechanism thereon, and back spacing mechanism on said main frame, said back spacing mechanism having a member arranged to engage the escapement mechanism for back spacing operations when said platen carriage frame is in operating position. 20
3. A typewriter comprising a main frame, a platen carriage frame pivotally mounted thereon, an escapement wheel mounted on said platen carriage frame, and back spacing mechanism on said main frame, said back spacing mechanism having a contact member extending into a position to cooperate with said escapement wheel when said platen carriage frame is in operating position. 30
4. The combination with an escapement wheel of a typewriter, of back spacing mechanism arranged to cooperate with said wheel, said back spacing mechanism having a contact member for engaging a tooth of said wheel the contact number being provided with a shifting pivotal connection with the axis of said wheel, and means for moving said member into engagement with said wheel and subsequently rotating said member about the axis of said wheel to impart a back spacing movement to said wheel. 40
5. The combination with an escapement wheel of a typewriter, of back spacing mechanism for said typewriter comprising a crank arm having means thereon for engaging a tooth of said wheel, and means for moving said arm radially of said wheel to bring said engaging means into contact with said wheel and for subsequently revolving said crank arm about the axis of said wheel to impart a back spacing movement to said wheel. 50
6. Back spacing mechanism for a typewriter comprising a crank arm having a sliding pivotal support, and means for sliding said arm on its support and subsequently rotating said arm thereon. 60
7. Back spacing mechanism for a typewriter having an escapement wheel, said mechanism comprising a crank arm having a pivotal support co-axial with said wheel and arranged to slide on said support, and a link connected with said crank arm for moving said crank arm in the direction of the length thereof to bring said arm into cooperative relation with said escapement wheel, said link being arranged to move said arm upon its pivotal support subsequent to said engagement for imparting a back spacing movement to said escapement wheel. 70
8. A typewriter comprising a pair of frame members movable relative to one another, an escapement wheel carried by one of said members and back spacing mechanism carried by the other of said members, said back spacing mechanism comprising a crank arm having a pivotal support co-axial with said escapement wheel when said escapement wheel is in operating position, means on said crank arm for engaging said escapement wheel but normally out of the path thereof, said arm being slidable upon its pivotal support for bringing said engaging means into cooperative relation with said escapement wheel, and means for sliding said arm on its support and for subsequently rotating said arm to impart a back spacing movement to said escapement wheel. 80
9. Back spacing mechanism comprising a crank arm having a pivotal support and a longitudinal slot engaging said support, a link pivoted to said crank arm, a stop for limiting the movement of said arm and link relative to one another, and a spring arranged to hold said link and crank arm in a position limited by said stop and by one end of said slot. 90
10. Back spacing mechanism comprising a link having a crank arm pivotally connected thereto, a sliding pivotal support for the opposite end of said crank arm, means for limiting the rotary movement of said crank arm upon its pivot, a spring for holding said crank arm at the limiting positions of its pivotal and sliding movement, and means for moving said link to slide said crank arm to the opposite end of its sliding movement and subsequently impart a rotary movement to said crank arm about its pivot. 100
11. A typewriter having an escapement wheel, back spacing mechanism therefor comprising a crank arm having a pivotal support co-axial with said escapement wheel, said crank arm being arranged to slide in the direction of the length thereof upon its pivotal support, a contact member carried by said crank arm for engaging the teeth of said escapement wheel, a link pivotally connected with said crank arm, means for limiting the movement of said crank arm about its pivotal support in one direction, resilient means for holding said crank arm in a position with said contact member out of the path of the teeth on said escapement wheel. 110

- wheel, and means for moving said link against the tension of said resilient means to first slide said link on its pivotal support to bring said contact member into engagement 5 with a tooth on said wheel, subsequent movement of said link swinging said crank arm and contact member about the axis of said escapement wheel to impart a back spacing movement to said escapement wheel.
- 10 12. A typewriter comprising a base frame, a platen carriage frame movable into and out of operating position on said base frame, escapement mechanism on said platen carriage frame comprising an escapement wheel, 15 back spacing mechanism on said main frame comprising a contact member for engaging said escapement wheel, means for holding said contact member in position to cooperate with said escapement wheel but out of the

path thereof when said platen carriage 20 frame is in operating position, and mechanism for moving said contact member into engagement with a tooth of said escapement wheel and subsequently rotating said member to impart a back spacing movement 25 to said escapement wheel.

13. A typewriter having a foldable platen carriage frame, an escapement wheel mounted on said frame, a main frame for supporting said platen carriage frame, and back 30 spacing mechanism arranged to operate directly on said escapement wheel when said platen carriage frame is in operating position.

In testimony whereof I have signed my 35 name to this specification on this 22nd day of August, A. D. 1921.

OTTO A. HOKANSON.
